PRESSURE FEED PENCIL

Kurt Fend, Pforzheim, Germany

Application January 31, 1938, Serial No. 187,977
In Germany April 29, 1937

10 Claims. (Cl. 120—17)

My invention relates to pressure feed pencils. Pencils of the general class to which my invention belongs are well known. Of the various pressure feed pencils known, those in which the lead core is pushed forward by means of a ratchet tong that can be locked with a ratchet ring dragged by the said ratchet tong have proven the most efficient. In this construction, the clamping of the lead core is especially reliable and guarantees a controlled and positive feed and retractive action. Pressure feed pencils of this kind, however, have the disadvantage that as each lead core is almost entirely used, there remains a remnant of lead which is held only by the ratchet of the pencil 10 point and not by the ratchet tong as well. This has a decided disadvantage. The ratchet tong is pushed partly into the ratchet ring until it is entirely stationary and takes back with it in this manner the lead which it grips. This retracting movement, however, is not shared by the aforesaid remnant of the lead remaining in the ratchet of the pencil point, so that an intervening space is created between it and the following lead which is gripped by the ratchet tong. In this space, the 15 remnant is pushed when writing pressure is brought to bear. This disadvantage is very disturbing in writing. A further disadvantage of these pencils lies in the fact that the remnant which is no longer held by the ratchet tong easily 20 rotates in the pencil point, and this makes writing difficult. Efforts have been made to overcome these disadvantages by pushing the ratchet tong up in the hollow space of the pencil point close to the opening in the tip thereof. This, of course, diminishes the length of the remnant of lead. However, in this case, the point of the pencil must be hollowed out close to the tip to fit the thickness of the tong and this weakens the point to such an extent that any shock, such as a 25 fall, damages it easily and thereby makes the entire pencil unusable.

There are also known pressure pencils in which two movable and spring actuated tongs are used. These do not, of course, show the cited disadvantages of the receding of the remnant and its rotating in the point. However, they have the disadvantage that they cannot use a tong cooperating with a loose ratchet ring and the advantages connected therewith and, in addition, cannot entirely retract the lead from the front when the same is not in use.

Finally, a construction of pressure feed pencil was proposed in which, in addition to a ratchet tong cooperating with a movable ratchet ring, a 30 movable point ratchet was used which was pushed

forward by the ratchet tong at the culmination of its forward movement. This pencil too, has the disadvantage that the remnant recedes backward when writing pressure is brought. In addition, the strong spring action actuating the ratchet point impedes the pushing of the lead through the ratchet point.

With the foregoing in view, an object of my invention is to provide a pressure feed pencil which overcomes all of the known disadvantages of known constructions and which combines all of the advantages of the prior art by using a ratchet tong which cooperates with a movable ratchet ring and which guarantees the rigid position of the lead core, as well as a sure and controlled feeding thereof.

A further object of my invention is to provide a pencil which prevents the undesirable retraction of a lead remnant when writing and which provides means for holding the said remnant tight in the ratchet point and preventing its rotation.

A still further object is to provide a pressure feed pencil with a ratchet tong which is controlled and movable against spring action and which can be locked by a movable ratchet ring, together with a spring controlled slidable ratchet point which, at the end of the forward movement of the ratchet tong, is pushed by it a short distance ahead. Such an operation consists in the fact that through the feeding action of the ratchet tong, the spring action is lifted from the ratchet point and the latter is forced backward again only after the total retraction of the ratchet tong, at which time said ratchet point again becomes subject to spring action, whereby the distance of forced travel of the ratchet point is at least as long as the ratchet way, in which the ratchet tong again takes back the lead which it has gripped.

The above form of construction makes it possible for the lead core which has been pushed forward by the ratchet tong and locked in forward position by means of the ratchet ring to overcome only a negligible resistance in the ratchet point, even when the latter is pushed back by means of spring action into a rigid position. In addition, the receding of the ratchet point at the end of the movement takes with it any remaining remnant of the lead core until it presses against the succeeding lead core held by the ratchet tong, so that it is rigidly seated and the writing action cannot push it back further. In addition, it is possible to push the lead core which protrudes from the point of the pencil entirely within the pencil when not in use by simply pushing it back

after the ratchet tong has been pushed forward and thereby released.

To obtain a certain and independent functioning of the ratchet tong and the tongue point, it is recommended to allow the lead core storing retainer which is mounted on the pressure cap function only after an empty run before feeding a lead to the ratchet tong, since even in the neutral position of the ratchet tong, lead core storing retainer and ratchet point, a further receding of the last two is made possible. This will correct inaccuracies of manufacture and irregularities in the thickness of the lead. The construction can provide a receiving piece which closes off the lead storage container forwardly and which is mounted on the rear part of the ratchet tong shaft, which said rear part projects into the lead storage container, and having a neck-shaped recess in front of said receiving piece in which a fork-shaped bearing piece is frictionally held that penetrates the lead storage chamber into two opposite slits and which bearing piece runs in two opposite openings with the ends which protrude from the slits, said openings being located in the shell connected to the tongue point. It has further been proven to advantage to mount the ratchet tong in a conduit which is carried inside the ratchet ring which is slidable between stops, and which conduit has on its outer surface two oppositely situated screw sections with which it penetrates the shell connected to the ratchet point by means of two openings, and has an intermediate shell screwed in its forward part, said intermediate shell being fixedly mounted to the outer shell. In this manner, the drawn-in forward edge of the intermediate shell will form a stop for a break of the shell mounted to the ratchet point.

The pressure feed pencil is provided, according to the invention, with two springs, one of which actuates the ratchet tong, while the other actuates the ratchet point. To obtain free action and with it a compact arrangement, the ratchet tong spring can rest with its forward part on the casing surrounding the ratchet tong and with its rear part on a connecting ring of the ratchet tong shaft. The spring actuating the ratchet point can rest with its forward part on a shell which rests on the casing. This shell bridges the ratchet tong spring. The ratchet point spring is arranged with its rear part resting against the forward part of the lead storage container.

Another embodiment is possible by permitting the spring actuating the ratchet point to rest with its forward part on the casing surrounding the ratchet tong, and with its rear part on the forward part of the lead storage container and where the ratchet tong spring is mounted forwardly of the ratchet tong and actuates the forward parts of the ratchet cheeks.

A pressure pencil according to the invention, can have a ratchet point shaped in various ways, as is well known in the art. The ratchet point can form directly the conically-shaped point of the pencil, or the ratchet point can be encased by the conically-shaped lead pencil point which in turn is fixedly connected to the outer casing, being drawn inside by means of a spring, whereby through the conical outer surfaces of the ratchet point the pressing action is increased.

All pressure pencils with a movable ratchet tong have in common a hollow space in front of the ratchet tong which permits the forward action of the ratchet tong during the lead feeding process. This hollow space must conform in its

width to the diameter of the ratchet tong and is therefore much wider than the thickness of the lead. The latter is not supported in this hollow space. Consequently, it breaks most frequently at this point and pieces of lead and graphite dust settle in this hollow space. This often leads to stoppages. It is an object of this invention to eliminate this disadvantage by filling the space between the ratchet point and the ratchet cheek by a tube which is pressed against the forward parts of the ratchet cheeks by means of a spring, said tube and tong moving forward in unison with the forward movement of the ratchet tong. This spring, by being made correspondingly stronger, can serve, at the same time, as a ratchet tong spring and thereby eliminates the necessity for an additional ratchet tong spring, together with the necessary parts to support it.

The spring motivated tube can further be used in known manner to force the spreading apart of the ratchet cheeks in the forward position of the ratchet tong by shaping the forward part of the ratchet cheeks conically inwardly and the rear part of the spring actuated tube conically outwardly in such manner that at the end of the forward movement of the rear part of the tube, the ratchet tong is spread apart.

With the foregoing and other objects in view, the invention consists in the details of construction, and in the arrangement and combination of parts to be hereinafter more fully set forth and claimed.

In the drawings, wherein, by way of examples, three embodiments of the invention are shown:

Fig. 1 is a longitudinal sectional view of one embodiment taken on the line I—I of Fig. 4 and showing the inner parts of the pencil in the neutral or retracted position;

Fig. 2 is a longitudinal sectional view taken on the line II—II of Fig. 4 and showing the inner parts of the pencil pushed forward;

Fig. 3 is a cross sectional view taken on the line III—III of Fig. 1;

Fig. 4 is a cross sectional view taken on the line IV—IV of Fig. 1;

Fig. 5 is an elevation, partly in longitudinal section, of a part of the pencil;

Fig. 6 is a top plan view of the pencil part of Fig. 5;

Fig. 7 is an elevation with portions in longitudinal section of another part of the pencil;

Fig. 8 is an elevation of the pencil part of Fig. 7, taken at right angles to Fig. 7;

Fig. 9 is an elevation with parts shown in longitudinal section of a second embodiment;

Fig. 10 is a longitudinal section of a further embodiment of the invention; and

Fig. 11 is a fragmentary longitudinal section of the upper end of the pencil.

The pressure feed pencil according to Figs. 1 to 4 has an outer casing 1, in the forward part of which is mounted a conical point 2. Within the outer casing 1 is an intermediate shell 3 which is fixedly connected to the casing 1, for instance, by means of soldering, and which intermediate shell 3 has its forward end reduced to form a neck 4, the inner periphery of which is provided with an impressed thread 4^a. The free end of the neck 4 is upset inwardly, as at 5. Threaded in the neck 4 is a tubular part 6, which latter is shown in elevation and plan, respectively, in Figs. 5 and 6. Part 6 is formed to provide on its outer side, two segmental externally threaded portions 7 arranged opposite to each other and taking up about one-quarter each of the circumference of 75

the neck 4. Between and inwardly of the periphery of these two threaded portions 7 are formed arcuate and smooth surfaced parts 8. The bore 9 of the part 6 is enlarged at its forward end as at 10, which enlargement is bounded rearwardly by a shoulder or stop 11 and forwardly by a stop 12 formed by an inwardly upset edge of the tube 6. A ratchet ring 13 which is slidable between the stops 11 and 12 is situated in the enlargement 10.

A shell 14 which is shown in Figs. 7 and 8 is slidably carried by the tube 6. The shell 14 has an enlarged rear part 15 of such diameter that it can be pushed over the threaded segments 7 of the tube 6. Near its rear part 15, the shell 14 is formed to provide two openings 16 positioned opposite to each other. The front end of the shell 14 is reduced to provide a neck 17 of a smaller inner diameter which is only large enough to permit the neck 11 to surround the smooth arcuate surfaces 8 which lie between the threaded segments 7. The neck 17 provides two facing openings 18 to permit the extension therethrough of the two segments 7, so that the portions intermediate the openings 18 consist of two narrow portions. The forward end of the neck 17 is further reduced to provide a neck 19 which forms a shoulder or stop 20 at its junction with the neck 17. The neck 19 has an internal thread 21 in which is threaded a tubular shell 22, the forward end of which is inwardly upset to provide a stop 23. A lead receiving tube 24 is slidably carried by the shell 22.

The tube 24 has a diameter sufficient for a sliding fit through the reduced opening formed by the inwardly upset edges 23 of the shell 22. The rear portion of the tube 24 is formed to provide an enlarged collar 25 which has a sliding fit against the inner periphery of the shell 22. The upper edges of the shell 22 are inwardly upset as at 26 to a lesser degree than the lower edges 23 to provide a stop. Thus, by the stops 23 and 26, and the collar 25, the sliding of the tube 24 in the shell 22 is definitely limited. The inner diameter of the tube 24 corresponds to the diameter of the lead.

The rear end of the tube 24 projects out of the rear end of the shell 22 and is formed to provide a conical point 26. The tube 24 is normally held in a retracted position by a spring 27 which is mounted in the shell 22 between the edge 23 thereof and the collar 25 of the tube 24. The neck 19 of the slidable shell 14 provides an outer thread 19^a on which the conical point 2 of the pencil is screwed. The bore of the point 2 varies in diameter to provide several stops. One reduced portion 29 is sized to have a sliding fit with the front end of the tube 24. The diameter of the extreme forward portion 30 of the bore corresponds to the diameter of the lead 31. The tip of the point 2 has been slotted longitudinally in the usual manner to provide a spring actuated ratchet point.

The tubular part 6 carries a ratchet tong tube 35 which is slidably mounted therein and which, in the known manner, is provided at its front end with resilient ratchet cheeks 36 by means of longitudinal slits formed therein. The cheeks 36 are spread outwardly by their own elasticity and are pressed against the lead to grip the same by the ratchet ring 13. The ratchet tong tube 35 carries at its rear end a conically-shaped hollowed out disk 37. A reduced neck 38 is formed on the tong tube 35 forwardly of and adjoining the disk 37. The neck 38 is bounded for-

wardly by a shoulder 39 which forms the start of an enlarged portion 40 of the tong tube 35. Portion 40 terminates forwardly in a shoulder 41 which connects portion 40 with a reduced portion 42, which in its turn is further reduced and slotted 5 to provide the ratchet tong cheeks 36 (see Fig. 4).

On the tube part 42 of the tong tube 35 is slidably mounted a collar ring 43 which forms the rear stop of a pressure spring 44 that rests with its forward end on the shoulder formed on 10 the tube part 6 by the enlarged portions 7. The rear end of the spring 44 engages the collar 43. The action of the spring 44 forces the collar 43 rearwardly against the shoulder 41 of the tong tube 35 and tends to force this tube rearwardly. The collar ring 43 and the spring 44 are enclosed within a bell-shaped shell 45 which is slidably mounted on the enlarged portion 40 of the ratchet tong tube 35. This shell 45 forms the forward support of a spiral spring 46 which 20 loosely surrounds the tube part 40. The rear end of the spring 46 rests against a shoulder 47^a formed between the forward end of a lead storage chamber 47 and a reduced neck 47^b there- 25 of which has a slidable fit with the tube part 40. Above the shoulder 47^a, the chamber 47 is formed to provide two facing transverse slits 48.

Through the slits 48, a fork-shaped carrier piece 49 extends in such a manner that it grips with its two fork arms 49^a the neck 38 of the 30 ratchet tong tube 35 and thus connects the lead storage chamber 47 with the ratchet tong, (see Fig. 3). Disk 37 on the rear part of the ratchet tong tube 35 forms a funnel-shaped bottom for the lead storage chamber 47, whereby fresh leads 35 are continually fed to the interior of the ratchet tong. The fork shaped carrier piece 49 is of such length that it extends beyond the openings 48 in the chamber 47 and its protruding ends 50, 50^a pass through the two openings 16 40 of the shell 14. The fork 49 is held in this position by means of the engagement of the ends 50, 50^a with the inner periphery of the slipped-over intermediate shell 3.

A lead 52 is shown supported in the ratchet tong tube 35 and rests upon the rear end of the lead 31 which is in use.

The rear end of my pressure feed pencil is the same in all forms and is shown in Fig. 11. On the rear end of the lead storage chamber 50 47 a pressure cap 51 is frictionally mounted which closes the chamber rearwardly.

The operation of this form of my pressure feed pencil is as follows:

In Fig. 1 (the neutral position), the position 55 of the inner parts shows the ratchet tong tube 35 pushed backward by spring 46 and this, in turn, causes the ratchet cheeks 36 to be rigidly drawn into the ratchet ring 13 and firmly pressed into engagement with the lead 52. The 60 point 2 is actuated by spring 46 which pushes the lead storage chamber 47 backwards and with it the fork-shaped carrier piece 49 and also, the shell 14 and the point 2 which is threadedly connected with the latter. This movement is 65 limited by the engagement of a stop 2^a formed on the point 2 with the forward edge of the outer casing 1. The forked carrier piece 49 slides rearwardly freely until it strikes the end disk 37 of the ratchet tong tube 35. The lead 31 held by the ratchet point 30 rests, as aforesaid, on lead 52. The conical rear part 26 of the tube 24 is actuated rearwardly by the spring 27 and rests on the forward bevelled faces of the ratchet tong cheeks 36. 70 75

By pressure on the button 51, the lead storage chamber 47, together with the carrier piece 49, is advanced without at first causing any movement of any other parts, against the action of the spring 46 until the carrier piece 49 strikes the shoulder 39 of the ratchet tong tube 35. This movement compresses the spring 46 and the carrier piece 49 travels away from the rear edge of the openings 16 of the shell 14. This relieves the point 2 from the back pressure of the spring 46 which had been transmitted thereto via the shell 14 and fork 49. In the continuing forward movement, the ratchet tong tube 35 is forced to participate. The ratchet tong carries lead 52 forward until the engagement of the ratchet ring 13 with the tong cheeks 36 is released through the ring engaging with the stop 12.

During this part of the movement, the point 2 remains unmoved and during this movement the lead 31 is pushed forward through the feed channel by the following lead 52. It is possible that the point 2, which is no longer pressed back by a spring 46, may advance with the lead 31 through the friction of the lead 31. Should this not occur, the point 2 is forced ahead in the latter part of the feeding movement after the fork-shaped carrier piece 49 comes to rest on the forward edges of the openings 16 of the shell 14, at which time it moves the shell 14 and point 2 forwardly. Lead 52 which has in the meantime been released as aforesaid, from ratchet cheeks 36 follows by gravity. The forward movement of the shell 14 is limited by the coming to rest of its shoulder or stop 20 (Fig. 2) on the inwardly up-set forward edge 5 of the intermediate shell 3.

During this process, the ratchet tong cheeks 36 push steadily against the conical end 26 of the tube 24. As soon as the ratchet ring 13 releases the ratchet cheeks 36, the latter spread apart. This spreading movement is furthered by the penetration between the cheeks 36 of the conical rear part 25 of the tube 24 by reason of the pressure of spring 27 and so spreads apart said cheeks.

Figure 2 shows the position of all parts at the conclusion of the feeding movement.

If the pressure on the button 51 is released, the latter returns to its original position by the action of spring 46. The ratchet tong 35 and the lead storage chamber 47, together with the fork-shaped carrier piece 49, recede under the action of springs 44 and 46. In this recession, the ratchet cheeks 36 do not carry back lead 52 until ratchet ring 13 which has receded also comes to rest at its rear stop 11 and closes the ratchet cheeks lightly. The ratchet cheeks are then drawn into the ratchet ring to stay fixed and, in this manner, carry with them the lead 52. Between lead 52 and the lead 31 held by the point a vacant space is temporarily formed. This is eliminated immediately, in that point 2 is also pushed back by the receding carrier piece 49 through shell 14 until the stop 2a of point 2 engages the forward edge of the outer shell 1. The moving path of the point 2 has been made at least equal to the "ratchet way" of the tong. In this way, the lead 31 is brought back along this path and again rests on the lead 52.

If the lead when being used for writing is so long that it is held by the ratchet tong as well as the point, this does not alter in any way the process of the pressure feed pencil, with the exception of the action of the "ratchet way" which does not occur.

In the embodiment of Fig. 9 in the forward part of the boring of shell 22a, a thread 22b is

cut, in which a tube 32 is screwed. The rear part 33 of the bore of tube 32 is enlarged to permit the forward movement of the tube 24. The internal diameter of the forward part of the tube 32 corresponds to the diameter of the lead 31 and is shaped through longitudinal slits to provide a ratchet point 34 with conical outer surfaces. In this embodiment, the narrowed internally threaded part 4c of the intermediate shell 3a is not reduced but is carried forward over the threaded segments 7 of the tube 6. In this threaded part 4c, a conical point 53 is screwed which adjoins the outer shell 1. The bore of the point 53 is enlarged at its rear part 54 to provide a channel for the shells 19b and 22a and is narrowed at its forward part 55 to provide a fixed pincher for the conically shaped outer surfaces 34a of the ratchet point 34. In all other respects, this embodiment is the same as in Figs. 1 to 8.

The operation of this pressure feeding pencil differs from that of the first embodiment, in that the point 53 is rigid and remains motionless during the feeding action. Instead, only the tube 32 which is screwed in the shell 22a is advanced by the shell 14a which is threaded at its neck 19b to the shell 22a. The feeding action is thereby limited, in that the stop 20a of the shell 14a comes to rest on the rear edge 53a of the point 53. The tube 32 is brought back at the end of the backward movement of the lead storage chamber 47. In this way, it takes back with it the balance of the lead 31 and eliminates thereby the space between leads 52 and 31 caused by the "ratchet way" of the ratchet tong of the first form.

In the writing position shown in Fig. 9, the ratchet point 34 is drawn into the forward channel 55 of the point 53 by means of a spring (not shown, but corresponding to the spring 46 of Figs. 1 and 2). This compresses the ratchet point and holds the lead 31 so rigidly that it cannot rotate.

The embodiment of the pressure feeding pencil of Fig. 10 shows an outer casing 1 and an intermediate casing 3b positioned within, whose reduced front end 4d has an internal thread 4e, in which a conical point 53a has been screwed. In addition, a tube 6 is screwed rearwardly in this thread 4e. The casing 3b carries a slidably shell 14b, whose forward reduced end 19c is extended, further reduced and slotted to provide the ratchet point 34b. In the tube 6, the ratchet tong tube 35 is positioned which is connected with its rear end to the lead storage chamber 47 by means of a fork-shaped carrier 49. At the forward part of the lead storage chamber 47, a pressure screw spring 46a is mounted with its forward end resting on the shoulder of the tube 6. In the reduced neck 19c of the shell 14b, a shell 56 is slidably mounted which, in turn, has a longitudinally slidable tube 24 and a spring 27 actuating this tube. The spring 27 presses the tube 24 against the forepart of the ratchet cheeks 36 of the ratchet tong tube 35 and forces the ratchet cheeks into the ratchet ring 13 which holds the lead 52 rigidly. This modification functions and operates in the same manner as the pressure feed pencil of Fig. 9.

I claim:

1. A pressure feed pencil including a casing, a storage chamber for leads slidably mounted in said casing at the rear end thereof, a tubular member slidably mounted in said casing adjacent said chamber and in axial alignment therewith, means to guide leads to the bore of said member from said chamber, the forward end of said

member comprising means for releasably gripping a lead in said member, means whereby sliding of said chamber towards the front end of said pencil advances said member and the lead gripped thereby, means for temporarily releasing said lead upon the sliding of said chamber and member in the opposite direction until the chamber and member have assumed their original positions, a connection between said member and chamber, said connection being operative to advance said member with said chamber only after the latter has been advanced a predetermined distance, a shell slidably mounted in said casing and surrounding said chamber and member, lead gripping means connected to the forward end of said shell, said connection between said member and said chamber being engageable with said shell to advance the same and said gripping means after the advance of said member has commenced.

2. A pressure feed pencil including a casing, a storage chamber for leads slidably mounted in said casing at the rear end thereof, a tubular member slidably mounted in said casing adjacent said chamber and in axial alignment therewith, means to guide leads to the bore of said member from said chamber, the forward end of said member comprising means for releasably gripping a lead in said member, means whereby sliding of said chamber towards the front end of said pencil advances said member and the lead gripped thereby, means for temporarily releasing said lead upon the sliding of said chamber and member in the opposite direction until the chamber and member have assumed their original positions, a connection between said member and chamber, said connection being operative to advance said member with said chamber only after the latter has been advanced a predetermined distance, a shell slidably mounted in said casing and surrounding said chamber and member, the forward end of said shell being formed to provide gripping means, said connection between said member and said chamber being engageable with said shell to advance the same and said gripping means after the advance of said member has commenced.

3. A pressure feed pencil including a casing, a storage chamber for leads slidably mounted in said casing at the rear end thereof, a tubular member slidably mounted in said casing adjacent said chamber and in axial alignment therewith, means to guide leads to the bore of said member from said chamber, the forward end of said member comprising means for releasably gripping a lead in said member, means whereby sliding of said chamber towards the front end of said pencil advances said member and the lead gripped thereby, means for temporarily releasing said lead upon the sliding of said chamber and member in the opposite direction until the chamber and member have assumed their original positions, the rear end of said member extending into said chamber and being outwardly flared to provide a funnel-shaped bottom therefor, a connecting member extending transversely across the lower end of said chamber below said flared end of said tubular member, a stop on said tubular member below and spaced from said connecting member and engageable therewith after said chamber has been advanced a predetermined distance whereby to cause said tubular member to be advanced with said chamber thereafter.

4. A pressure feed pencil including a casing, a storage chamber for leads slidably mounted in

said casing at the rear end thereof, a tubular member slidably mounted in said casing adjacent said chamber and in axial alignment therewith, means to guide leads to the bore of said member from said chamber, the forward end of said member comprising means for releasably gripping a lead in said member, means whereby sliding of said chamber towards the front end of said pencil advances said member and the lead gripped thereby, means for temporarily releasing said lead upon the sliding of said chamber and member in the opposite direction until the chamber and member have assumed their original positions, a shell slidably mounted in said casing and surrounding said chamber and member, lead gripping means connected to the forward end of said shell, the rear end of said member extending into said chamber and being outwardly flared to provide a funnel-shaped bottom therefor, a connecting member extending transversely across the lower end of said chamber below said flared end of said tubular member, a stop on said tubular member below and spaced from said connecting member and engageable therewith after said chamber has been advanced a predetermined distance whereby to cause said tubular member to be advanced with said chamber thereafter, the ends of said connecting member extending beyond said chamber and being engageable with said shell to advance the same after said chamber has been advanced a predetermined distance.

5. A pressure feed pencil including a casing, a storage chamber for leads slidably mounted in said casing at the rear end thereof, a tubular member slidably mounted in said casing adjacent said chamber and in axial alignment therewith, means to guide leads to the bore of said member from said chamber, the forward end of said member comprising means for releasably gripping a lead in said member, means whereby sliding of said chamber towards the front end of said pencil advances said member and the lead gripped thereby, means for temporarily releasing said lead upon the sliding of said chamber and member in the opposite direction until the chamber and member have assumed their original positions, a shell slidably mounted in said casing and surrounding said chamber and member, lead gripping means connected to the forward end of said shell, the rear end of said member extending into said chamber and being outwardly flared to provide a funnel-shaped bottom therefor, a connecting member extending transversely across the lower end of said chamber below said flared end of said tubular member, a stop on said tubular member below and spaced from said connecting member and engageable therewith after said chamber has been advanced a predetermined distance whereby to cause said tubular member to be advanced with said chamber thereafter, the ends of said connecting member extending beyond said chamber and being engageable with said shell to advance the same after said chamber has been advanced a predetermined distance, said connecting member being engageable with said flared end of said tubular member and also with said shell to retract the twain after said chamber has been retracted a predetermined distance.

6. In a pressure feed pencil, a ratchet ring slidably mounted in said pencil for limited movement axially thereof, a hollow, spring actuated, slidable lead gripping ratchet tong within said pencil and extending through said ring, a spring

- actuated lead gripping means slidably connected to one end of said pencil forwardly of said tong, springs for actuating said means and tong, means for feeding axially alined leads to said gripping means through said hollow tong, said mounting means for said ring comprising a tube mounted in said pencil adjacent the front end thereof, a portion of the bore of said tube being enlarged to provide a limited slideway for said ring, said lead advancing means including a shell surrounding said tong and tube and connected to said lead gripping means, said shell being formed to provide apertures therethrough in the region of said tube, and means connecting said tube to said pencil through said openings in said shell, said connecting means and opening being of a size to permit limited axial sliding movement of said shell in said pencil.
7. In a pressure feed pencil including an outer casing, a conical point at one end thereof, a lead storage magazine slidably carried by the other end of said casing and a guide tube axially of said casing for guiding leads from said magazine to said point, the forward end of said tube terminating within said casing short of said point, means integral with said forward end of said tube for gripping a lead guided by said tube, and means carried by said casing and operative to actuate said gripping means to grip and advance a lead when said magazine is slid forwardly towards said point, to actuate said gripping means to release said lead when said magazine is slid rearwardly a predetermined distance and then to actuate said gripping means to re-grip said advanced lead.
8. In a pressure feed pencil including an outer casing, a conical point at one end thereof, a lead storage magazine slidably carried by the other end of said casing and a guide tube axially of said casing for guiding leads from said magazine to said point, the forward end of said tube terminating within said casing short of said point, means integral with said forward end of said tube for gripping a lead guided by said tube,
- and a ratchet ring carried by said casing and surrounding said tube adjacent said forward end thereof, said ring being operative to actuate said gripping means to grip and advance a lead when said magazine is slid forwardly towards said point, to actuate said gripping means to release said lead when said magazine is slid rearwardly a predetermined distance and then to actuate said gripping means to re-grip said advanced lead to support the same in a writing position additional lead gripping means carried by said point, means for advancing said additional lead gripping means during a portion of the advance of said lead, and means for retracting said additional gripping means and lead after said first gripping means has been retracted and has re-gripped said lead.
9. In a pressure feed pencil including an outer casing, a conical point at one end thereof, a lead storage magazine slidably carried by the other end of said casing and a guide tube axially of said casing for guiding leads from said magazine to said point, the forward end of said tube terminating within said casing short of said point, said forward end being slotted to provide lead gripping tongs, cam surfaces on the peripheries of said tongs, and means carried by said casing and normally engaging said surfaces to cause said tongs to grip a lead guided by said tube to support the same in a writing position and to advance said lead when said magazine is slid forwardly, but said means temporarily disengaging said surfaces to permit said tongs to release their grip on an advanced lead while said magazine and tube is slid rearwardly a predetermined distance over said advanced lead additional lead gripping means carried by said point, means for advancing said additional lead gripping means during a portion of the advance of said lead, and means for retracting said additional gripping means and lead after said tongs have been retracted and have re-gripped said lead.
10. The structure of claim 9, said means comprising a ratchet ring carried by said casing and surrounding said slotted end of said tube, said ring being slidable relative to said casing and tube, and means actuating said ring to engage and disengage with said cam surfaces as aforesaid.
